WINDOW VALANCE

George E. Eckert, Fort Atkinson, Wis., assignor
to Moe Light, Inc., Fort Atkinson, Wis., a cor-
poration of Wisconsin

Application September 15, 1950, Serial No. 12,196

Term of patent 14 years

(Cl. D21—6)

To all whom it may concern:

Be it known that I, George E. Eckert, a citizen of the United States, residing at Fort Atkinson, in the county of Jefferson, State of Wisconsin, have invented a new, original, and ornamental Design for a Window Valance, of which the following is a specification, reference being had to the accompanying drawing, forming part thereof.

Fig. 1 is a perspective view of a window valance, showing my new design.

Fig. 2 is a top plan view thereof.

Fig. 3 is a fragmentary enlarged cross-sectional view thereof, taken on line 3—3 in Fig. 1.

Fig. 4 is an enlarged cross-sectional view thereof, taken on the line 4—4 in Fig. 3; and

Fig. 5 is an enlarged cross-sectional view thereof, taken on the line 5—5 in Fig. 1.

The characteristic feature of my design resides in the end portions of the valance and their

relation to and association with the central section.

I claim:

The ornamental design for a window valance, as shown and described.

GEORGE E. ECKERT.
